UNITED STATES PATENT OFFICE.

CHARLES A. LATIMER, OF TOLEDO, OHIO.

SHINGLE-STAINING MACHINE AND PROCESS OF STAINING.

Application filed December 19, 1925. Serial No. 76,399.

My invention has for its object to provide a process of producing an exceedingly durable stain on articles of wood particularly shingles, that is regulable as to its duration, whereby shingles may be stained to a depth according to the durability of the shingle itself which is dependable largely on the character of the wood from which the shingle is formed. In the process involved in my invention, the shingles or other articles of wood may be rapidly stained and the process provides for handling the stain at a very low cost and involves the use of a comparatively small amount of stain. The invention also involves the apparatus wherein the process may be conducted to rapidly stain shingles at a very low cost.

The invention may be contained in processes and machines or apparatuses which vary in their details. To illustrate a practical application of the invention I have selected a process as an example of such processes and shall describe it hereinafter, together with an apparatus in which the process may be conducted. The apparatus is shown in the accompanying drawings and is also described hereinafter.

Figure 1 of the drawings illustrates a longitudinal section through the apparatus in which the process is conducted. Fig. 2 is an end view of the apparatus shown in Fig. 1.

In the process involving the use of my invention, the stain is forced into the wooden articles by subjecting the stain in which the articles are submerged to a pressure that may be regulated as to amount and as to duration of time and in order that the wooden articles, such as, the shingles, may be handled without injury to the stained surfaces, immediately as the stain is withdrawn. A vacuous condition is created by withdrawal of the stain from a sealed container having suitable adjusting limiting or sealing valves whereby the shingles or other articles of wood may be removed from the container shortly after or substantially upon the withdrawal of the stain from the shingles. This may be accomplished by the apparatus shown in the figures. The apparatus is provided with a stain box 1 which is supported on a frame 2, it being provided with suitable cross bars 3 for withstanding the pressure to which the surfaces of the box are subjected. The box may be provided with a track 4 for supporting a truck or frame or rack 5

on which the shingles 6 may be piled in any numbers within the limitations of the box and preferably with their surfaces in vertical planes. The rack 5 may be slid on to the track 4 which may be if desired provided with rollers or any other suitable means which will enable the rack 5 to be readily slid into the box. The box 1 is preferably of a size sufficient to have very little additional room besides that which is occupied by the rack 5 and its load of shingles. The end of the box 1 is closed by means of a vat 10 formed in a casting 13 that is secured to the end of the box 1. The channel 12 may be provided with suitable packing 14 and a threaded wheel 15 operates upon a screw 16 to force the gate 10 so that the flange 11 will be tightly pressed against the packing in the channel of the casting 13. The wheel 15 is rotatably secured in a plate 17 that may be hinged to the casting 13 or to the supporting frame 2. In order to open the gate 10 a pin or pintel 18 may be removed, when the screw 16 has been released by rotation of the wheel 15, and the gate 10 and the plate 17 may be rotated on the other pintel such as the pintel 19 of the hinge. The rack 5 may then be inserted endwise into the box 1. The stain may then be introduced into the box 1 for staining the load on the rack.

The stain is normally contained in the vat 20. An agitator 21 may be located in the bottom of the vat. It consists of a paddle 22, a shaft 23 having bearings in the top and bottom of the vat, and a handle 24 that may be oscillated back and forth to cause the material to be agitated particularly at the bottom to maintain a substantially uniform mixture of the oils and paints, etc., that make up the stain. A pipe 25 extends to the bottom of the vat, its inlet being provided with a suitable strainer 26. A pump 27 is connected to the pipe 25 and operates to draw the stain from the vat. The pump 27 delivers the stain to the container 1 through the pipe 28, which has its outlet preferably at the bottom of the staining box 1. The stain may then be forced into the bottom of the container 1. The pump is also preferably a reversible pump whereby the stain may be drawn from the stain box 1 and directed through the pipe 25 into the vat 20. In order to prevent sawdust or other materials from entering the pump and the vat, a strainer 29 is located at the

point of connection between the pipe 28 and the bottom of the staining box 1. The staining box 1 may thus be completely filled with the stain and emptied by the operations of

5 the pump.

The stain is preferably forced into the box 1 under pressure until the box is completely filled. The pump is operated until the stain is forced by a valve 32. The valve 32 is 10 spring pressed, by means of the spring 33, on its seat 34. The pressure of the spring 33 is adjusted by means of the handle 35 which has a threaded shank 36. The pressure of the spring 33 is regulated preferably 15 from seven to twenty pounds of pressure per square inch so that when the pressure within the box 1 exceeds the predetermined amount as limited by the adjustment of the spring 33, the stain will fill the box 1 and 20 will eventually pass through the valve seat 34 into the pipe 37 and return to the vat 20. If desired the valve 32 may be opened while the pump is operating to fill the box 1 until the stain flows into the vat 20 from the pipe 25 37 whereupon the adjustment of the pressure of the spring 33 may be made by rotation of the handle 35. When the pressure produced within the box has raised sufficient to cause the flow of the stain through the valve seat 30 34, according to the adjustment of the pressure of the valve, the pump is reversed to withdraw the stain from the box 1 and return it to the vat 20. This is preferably done immediately, and as soon as the vat has 35 been emptied, against the back pressure of the atmosphere, the shingles will be in condition for removal since they will be completely dried by the vacuous condition which is created by the withdrawal of the stain.

40 The vacuous condition within the box 1 may be adjusted by means of an inlet valve 40 which is spring pressed by means of the spring 41 which is adjusted by means of the handle 42 having a threaded shank 43. As 45 the level of the stain lowers in the container 1 the vacuous condition above the surface of the stain will be maintained at substantially a constant pressure, a pressure that is below that of the atmosphere, which is controlled by the adjustment of the tension of the spring 41. By the time that the level of the stain has receded from the shingles, the box may be opened and the shingles removed. Preferably the stain is quite 50 completely removed from the box 1 the box is opened and the shingles removed. In order that the gate 10 may be readily opened, I have provided a valve 45 which may be easily opened to allow free movement of the 55 air into the box 1 to relieve the excess external pressure on the door. The wheel 15 may then be rotated and the door 10 may be opened. The rack 5 together with its load 60 may be drawn from the box and another loaded rack may be immediately inserted,

the gate 10 closed, the pump started, and reversed and so on continuously. Thus shingles may be stained rapidly and efficiently and to any desired depth.

The depth of the stain of the shingles will 70 depend upon the degree of liquefaction of the pigment and upon the pressure to which it is subjected. This depth will also depend upon the character of wood of which the shingles are formed. Preferably, the 75 depth of the stain is controlled according to the durability of the shingles. If the wood of the shingles is such that the life of the shingle will be greater, the stain will be caused to penetrate accordingly. This provides for the saving of the stain and 80 enables a charge for the shingles according to the life of the wood taken in conjunction with the added life by reason of the stain of the shingle. Thus the life of the shingle 85 as a whole is greatly extended and the amount of stain utilized may be controlled according to the life of the shingle as a whole. The invention thus provides for a 90 very exact control of the stain, both as to cost of the stain to produce the maximum results or to produce the exact results that may be desired according to the character 95 of the wood.

In order that the pump 27 may be readily 95 operated, it is driven by means of a suitable motor 47 having a reversing clutch 48 that may be actuated by means of a lever 49 to reverse the operations of the pump in the 100 manner well known in the art.

I claim:

1. In an apparatus for staining shingles and the like a staining box for containing the shingles, a vat for containing the stain, a pipe connecting the upper end of the box 105 with the vat and having a spring-pressed outlet valve located in the pipe, a pump, a pair of pipes, one for connecting the pump to the lower end of the box and the other for connecting the pump with the vat, the pump operating to draw the stain from the vat and force it into the box and out through the pressure valve and the first named pipe into the vat, and maintain a pressure above 110 atmosphere during the movement of the stain, means for reversing the pump, for drawing the stain from the box and directing it into the vat to form a vacuum during the reverse operation of the pump.

2. In an apparatus for staining shingles and the like a staining box for containing the shingles, a vat for containing the stain, a pipe connecting the upper ends of the box with the vat and having a spring-pressed outlet valve located in the pipe, a pump, a pair of pipes, one for connecting the pump to the lower end of the box and the other for connecting the pump with the vat, the pump operating to draw the stain from the vat and force it into the box and out through 115 120 125 130 135 140 145 150 155 160 165 170 175 180

the pressure valve and the first named pipe into the vat and maintain a pressure above atmosphere during the movement of the stain, means for reversing the pump for drawing the stain from the box and directing it into the vat to form a vacuum during the reverse operation of the pump, a spring-pressed inlet valve connected to the top of the box for admitting air when the vacuous condition reaches a predetermined degree ¹⁰ while the pump is drawing the stain from the box.

In testimony whereof I have hereunto signed my name to this specification.

CHARLES A. LATIMER.
